RAIL BOND

Jacob B. Beam, Punxsutawney, Pa., assignor to
Punxsutawney Electric Repair Co., Inc., Punxsutawney, Pa., a corporation of Pennsylvania

Application May 10, 1940, Serial No. 334,455

2 Claims.

(Cl. 173—283)

This invention is a novel improvement in terminals for rail bonds, particularly those used in the light gauge railways of mines or the like where the rails must be constantly shifted rendering ordinary rail bonds subject to rapid deterioration.

The present invention is an improvement upon the rail bond shown in U. S. Letters Patent No. 1,748,532, dated February 25, 1930, and the principal object thereof is to provide a novel rail bond terminal having a split rail engaging boss whereby it may be expanded by means of a tapered bolt to snugly fit a hole formed in the web of the rail adjacent the joint, said terminal also having a split wire or cable receiving socket adapted to receive and bind the end of bonding wires or cables of various sizes, said socket being contracted by the same tapered bolt which expands the rail engaging boss, the one tapered bolt thus serving the double function of securing the terminal to the rail and securing the bonding wire in the socket of the terminal as the bolt is drawn into place in the terminal. By the above construction, in event a car should become de-railed and thereby break or cut the bonding wire or cable, the tapered bolt need merely be loosened in the terminal without removing the terminal from the position in the rail, and a new length of bonding wire or cable, of any one of various different odd or regular sizes, inserted in the socket, whereby when the bolt is again tightened the socket will be contracted around the end of the wire or cable with a minimum amount of time and effort required to make the repair.

Other minor objects of the invention will be hereinafter set forth.

I will explain the invention with reference to the accompanying drawing, which illustrates one practical embodiment thereof to enable others to adopt and use the same; and will summarize in the claims, the novel features of construction, and novel combinations of parts, for which protection is desired.

In said drawing:

Fig. 1 is a side elevation showing adjoining rail sections connected by a rail bond constructed in accordance with my invention.

Fig. 2 is an enlarged horizontal section on the line 2—2, Fig. 1.

Fig. 3 is a side elevation of the rail bond terminal, detached.

Fig. 4 is a top plan view of said terminal.

Fig. 5 is a socket end view of said terminal.

My novel terminal comprises a U-shaped body 1, made of copper or other soft, yieldable metal

having electrical conductivity, said body having one face 1a adapted for contact directly with the web of the rail R as shown in Fig. 2. Projecting from face 1a is a cylindrical boss 1b adapted to enter a circular hole R' (Fig. 2) formed in the web of rail R adjacent the rail joint. Body 1 is provided with a transverse tapered bore 1c passing through both legs of the body axially of boss 1b, for the reception of a conical spreader bolt 2, the larger end of which bolt is disposed within the boss 1b, while the smaller end thereof has a threaded extension 2a for a nut 3, said nut abutting the outer face 1d of body 1, although if desired a lock washer 4 may be inserted between nut 3 and body face 1d as shown in Fig. 2. Boss 1b is split diametrically as at 1e, and the split is continued well into the face 1a of the body at each side of the base of boss 1b as shown in Fig. 2, so as to permit the walls of the boss to be readily spread apart in hole R' of the rail as the spreader bolt 2 is tightened by nut 3. Said tightening of nut 3 causes the walls of the head and boss to spread with the result that the side walls of the boss very firmly engage the walls of the hole R' to establish a good and rapidly applied electrical connection therewith, with very little tendency to rupture the metal of the body 1.

In the outer portions of the legs of body 1 are opposed substantially semi-circular recesses 1f together forming a split socket for receiving the end of a bonding wire or cable W which may be inserted in the socket. The semi-circular recesses 1f, as shown in Fig. 2, extend inwardly substantially to the tapered bore 1c for the bolt 2 and are preferably disposed on the axis of the body 1 in line with the axis of bolt 2, so that the tightening of nut 3 will not only spread the split boss 1b to bind the terminal in the holes R' in the rail, but simultaneously the legs of the body will be drawn together to contract the split socket formed by the recesses 1f around the end of the cable or wire W inserted therein.

Thus the wire or cable W will be rigidly clamped with good electrical connection to the terminal body without the use of solder or other extraneous fastenings; and by reason of the split socket portions 1f, various odd or regular sizes of wire or cable W can be used in connection with my terminal irrespective of whether the wire is solid or stranded. Companies using rail bond terminals usually have on hand one or more sizes of used trolley wire or the like among their scrap, and lengths of such scrap wire may be readily utilized to effect an efficient bond utilizing my terminal. In actual test my

terminal has been successfully used with strand wires of the following sizes: .2893, .3249, .3648, and .4096; and with solid wire of the following sizes: .2578, .2893, .3249 and .3648. Thus in event the bonding wire or cable should be broken by a car jumping the rail or otherwise, it is not necessary that the body 1 be removed from the rail. It is only necessary that the nut 3 be loosened to permit the split socket 1f to expand, and the broken wire or cable may then be removed and a new length of wire or cable inserted in the socket, after which the nut 3 would then be tightened on the bolt 2. Replacement of a broken bonding wire or cable W utilizing my terminal may thus be effected with a minimum amount of time and labor, and without removing the terminal from the rail, the single tapered bolt 2 serving the double function of expanding the boss 1b in the hole R' of the rail, and at the same time contracting the split socket 1f around the end of the cable or wire inserted therein.

I do not limit my invention to the exact details shown in the drawing, for obviously changes may be made therein within the scope of the claims.

I claim:

1. A bond terminal for rails having holes in the webs thereof, comprising an integral yieldable U-shaped body of electrically conductive material having aligned bores extending through the legs thereof, and having a split cable receiving socket formed by opposed recesses in the outer portions of said legs; an expansible boss of slightly less size than the hole in the rail web extending from the outer side of one leg and having a bore extending therethrough registering with the first mentioned bores; a bolt having a boss expanding head of less maximum diameter than the aperture in the rail flange con-

fined in the bore of the boss and having a shank extending through the first mentioned bores; and a nut threaded on the shank and engaging the outer side of the other leg whereby upon loosening the nut said boss may be inserted in the hole in the rail web and a bonding cable of various different types and sizes inserted in the split socket without removing the bolt and nut from the body, and upon subsequent tightening of the nut said bolt will expand the boss and secure the body to the rail to bind the end of the cable therein.

2. A bond terminal for rails having holes in the webs thereof, comprising an integral yieldable U-shaped body of electrically conductive material having aligned bores extending through the legs thereof and having a split cable receiving socket formed by opposed recesses in the outer portions of said legs; a split boss of slightly less size than the hole in the rail web extending from the outer side of one leg and having an outwardly tapering bore extending therethrough registering with the first mentioned bores; a bolt having a correspondingly tapered head of less maximum diameter than the aperture in the rail flange disposed in the tapered bore and having a shank extending through the first mentioned bores; and a nut threaded on the shank and engaging the outer side of the other leg, whereby upon loosening the nut said boss may be inserted in the hole in the rail web and a bonding cable of various different types and sizes inserted in the split socket without disassembling the bolt and nut from the body, and whereby upon subsequent tightening of the nut said bolt will expand the boss and secure the body to the rail and simultaneously contract the socket to bind the end of the cable therein.

JACOB B. BEAM.
